UNITED STATES PATENT OFFICE

GUY W. BLACKBURN, OF ELGIN, ILLINOIS, ASSIGNOR TO FRED W. GUSIE, OF ELGIN, ILLINOIS

CIGARETTE CASE

Application filed May 20, 1929. Serial No. 364,424.

My invention relates to improvements in cigarette cases and has for one object to provide a new and improved form of cigarette case wherein the package in which the cigarettes are originally shipped may be closely held and wherein such package after it has been placed in the cigarette case may be automatically opened for dispensing cigarettes. Another object is to provide a cigarette case which will contain the cigarette package and which will have associated with it means for severing the end of the package on three sides and tearing back the unsevered side to expose the cigarettes for a sufficient distance inwardly from their exposed ends to make it easy to withdraw them from the package. Another object is to provide a cigarette case which will hold the cigarettes in the package, open the package and which will hold the package and cigarettes in proper relation during use. Other objects will appear from time to time throughout the specification and claims.

My invention is illustrated more or less diagrammatically in the accompanying drawings, wherein—

Figure 1 is a front elevation;

Figure 2 is a side elevation;

Figure 3 is a view similar to Figure 2 showing the cover open;

Figure 4 is a plan view with cover opened and cutting knives withdrawn;

Figure 5 is a reversed view of the cover with knives withdrawn;

Figure 6 is a plan view with cover closed and knives inserted in the closed position;

Figure 7 is a plan view with cover opened and knives in the inner position;

Figure 8 is a section along the line 8—8 of Figure 1;

Figure 9 is a section along the line 9—9 of Figure 8.

Like parts are indicated by like characters throughout.

A is a receptacle or housing having an open end closed by a hinged cover A¹, the pivot axis of the hinge A² being located at a point below the open end of the case. A³ is a latch mounted on a spring A⁴ adapted to lock the cover in position on the case. A⁵

is a release button adapted to work on the spring to release the latch. A⁶ is a spring engaging the cover adapted normally to yieldingly urge it into the open position.

The case snugly fits the package adapted to be contained within it. As illustrated the device is applied to a cigarette package. The cigarettes B are contained within a paper receptacle having side walls B¹ and an end piece B², this end piece projecting just above the upper end of the case when the package is seated in it. Slidably mounted in the pivoted cover are two end slides B³ B⁴ and a side slide B⁵. These slides may be withdrawn as indicated or forced home as indicated by means of flanges B⁶ B⁷ which project far enough above the end of the cover to be easily grasped. These slides are inferiorly enlarged as indicated so as to limit their withdrawal from the cover. Associated with the two slides B³ B⁴ are knife blades B⁸ B⁹, these knives being sharply pointed and associated with the slide B⁵ is a serrated knife B¹⁰. These knives by virtue of their mounting on the slides are positioned just under the inner wall of the cover, there being sufficient clearance between them and the cover to receive the end of the package as indicated. When the package is assembled in the case with the parts in the position shown, for instance in Figure 4, if the cover is then closed over the case the slides and associated knives may be forced home penetrating and severing three of the side walls of the package and holding the end of the package snugly between the knives and the underside of the cover.

There is no knife on the hinge side of the cover. The wall of the case is cut away down as far as the hinge so that when the cover is opened, the end of the case being held in the cover. Rotation of the cover causes tearing of the side wall of the package adjacent the unsevered portion of the end so as to leave a clearance inwardly from the end of the receptacle down to the hinge so that cigarettes and the like may be easily seized for withdrawal.

The use and operation of my device are as follows:

The hinged cover of the case is open. The assembled cigarette package is inserted in the case and the cover is closed. The three cutting blades will be withdrawn before the cover is closed and when the cover is closed will be forced inwardly cutting or severing the side of the package immediately beneath the closed end on three sides. This serves to hold the severed end of the package in place on the cover. Then since the cover is pivoted slightly below the end of the case and below the end of the package when the cover is opened, this will tend to tear back the unsevered side of the package for a short distance exposing the sides of the cigarettes along the unsevered side of the package for a short distance downwardly from their ends and providing a convenient place where the cigarettes may be seized for withdrawal from the case. The severed partially torn off end of the package will be retained in the case during use thus serving to permanently position the wrapper or package in the case and permitting continued use of the end as a packing or closure for the package so as to cushion the cigarettes and tend to maintain them in the same condition that they were when the package was open. This packing or cushioning effect also prevents leakage of tobacco fragments, dust and the like from the case into the pocket of the user.

While this invention is primarily intended for use in connection with cigarette packages, it is obvious that the device may be applied and used with any type of paper or fabric package which can be fitted into a case, the end of which can be severed so that the end in the pivoted cover may be used as a closure to retain material while being used, dispensed or stored. The invention might be applicable to breakfast foods, salt packages, packages containing loose tobacco, sugar, chemicals and the like.

I claim:

1. A receptacle adapted to contain a closed severable package, a pivoted latched cover for one end thereof, means mounted in the cover for severing the end of the package on three sides thereof and for gripping the severed end in the cover, the cover being hinged at a point below the end of the receptacle whereby when the cover is opened after severing the end of the package, the side of the package adjacent the unsevered portion will be torn back a short distance.

2. A receptacle adapted to contain a closed severable package, a pivoted latched cover for one end thereof, means mounted in the cover for severing the end of the package on three sides thereof and for gripping the severed end in the cover, said means comprising knives mounted in the cover, said knives being adapted to be withdrawn when the package is first inserted in the receptacle to clear the cover and adapted to be forced in-

wardly through the side walls of the package immediately beneath the end to hold and grip the severed end in position in the cover.

3. In combination, a receptacle adapted to receive a severable package, a pivoted closure for the open end of the receptacle, slides mounted for reciprocation in the closure and held within limits of reciprocation, knives mounted on the slides adapted when the slides are in their outermost position to clear the package and adapted when the slides are in their innermost position to penetrate the package and grip the end thereof between their upper surfaces and the underside of the cover.

4. A receptacle adapted to contain a closed severable package, a pivoted latched cover for one end thereof, means mounted in the cover for severing the end of the package, and for gripping the severed end in the cover, including a knife slideable in the cover at a level below the top of the package, said knife being adapted to confine the top of the package between itself and the cover, after the severing of the top.

5. A receptacle adapted to contain a closed severable package, a pivoted latched cover for one end thereof, means mounted in the cover for severing the end of the package, and for gripping the severed end in the cover, including a knife slideable in the cover at a level below the top of the package, said knife being adapted to confine the top of the package between itself and the cover, after the severing of the top, the cover being hinged at a point below the end of the receptacle, whereby when the cover is opened after severing the end of the package, the side of the package adjacent the unsevered portion will be drawn back a short distance.

6. The structure of claim 4 characterized by the employment of means for holding the cover normally in closed position.

7. The structure of claim 4 characterized by the employment of means for normally holding the cover in closed position, and yielding means for opening the cover when the closing means are released.

8. A receptacle adapted to contain a closed package of cigarettes having a severable wrapper, said receptacle having an openable cover for one end thereof, means associated with the cover for partially severing the wrapper in a plane transverse to the long axes of the cigarettes and adjacent the ends of the cigarettes and for gripping and holding the partially severed end of the wrapper in the cover, whereby the said ends of the cigarettes will be exposed for convenient access and axial removal when the cover is open.

9. A receptacle adapted to contain a closed package of cigarettes having a severable wrapper, said receptacle having an openable cover for one end thereof, means for partially severing the wrapper in a plane transverse to

the long axes of the cigarettes and adjacent the ends of the cigarettes and for gripping and holding the partially severed end of the wrapper in the cover, whereby the said ends of the cigarettes will be exposed for convenient access and axial removal when the cover is open.

10. A receptacle adapted to receive a closed package of cigarettes having a severable wrapper, a cover for one end of said receptacle, and means associated with the cover for partially severing the wrapper in a transverse plane between the ends of the cigarettes adjacent the cover and that portion of the wrapper which normally overlies said ends of the cigarettes, and for gripping and holding the partially severed end of the wrapper in the cover, whereby the said ends of the cigarettes are uncovered and exposed for convenient access and removal when the cover is open.

11. A receptacle adapted to receive a closed package of cigarettes having a severable wrapper, a cover for one end of said receptacle, and means associated with the cover for partially severing the wrapper in a transverse plane between the ends of the cigarettes adjacent the cover and that portion of the wrapper which normally overlies said ends of the cigarettes, and for gripping and holding the partially severed end of the wrapper in the cover, whereby the said ends of the cigarettes are uncovered and exposed for convenient access and removal when the cover is open, said cover being pivoted along an axis transverse to the axes of the cigarettes along a plane below the end of the package opposed to the cover, whereby when the cover is opened after severing the end of the package, the upper edge of the side of the package adjacent an unsevered portion will be torn downwardly a short distance.

Signed at Chicago, county of Cook and State of Illinois, this 15th day of May, 1929.

GUY W. BLACKBURN.
